UNITED STATES PATENT OFFICE

103,925

DESIGN FOR A CORNER KITCHEN SINK

Helen G. Carlton, Baltimore, Md.

Application September 16, 1936, Serial No. 64,877

Term of patent 7 years

To all whom it may concern:

Be it known that I, Helen G. Carlton, a citizen of the United States, residing at Baltimore (independent city), and State of Maryland, have invented a new, original, and ornamental Design for a Corner Kitchen Sink, of which the following is a specification, reference being had to the accompanying drawing, forming part thereof.

I claim:

The ornamental design for a corner kitchen sink, as shown.

HELEN G. CARLTON.
